UNITED STATES PATENT OFFICE.

WALTER B. BARROWS, OF NORWICH, CONNECTICUT, ASSIGNOR TO MEYER GOLDEN, OF NEW YORK, N. Y.

DESIGN FOR A SUSPENDED STAGE CHAIR.

Application filed January 11, 1929. Serial No. 29,570. Term of patent 3½ years.

To all whom it may concern:

Be it known that I, WALTER B. BARROWS, a citizen of the United States, residing at the city of Norwich, State of Connecticut, county of New London, have invented a new and original Design for Suspended Stage Chair, of which the following is a specification, reference being had to the accompanying drawing, forming part thereof.

Fig. 1 is a front view of a suspended stage chair showing my new design, the ornamenta-

Fig. 2 is a top view of the same, the seat and foot rail as shown projecting forwardly of the frame.

I claim:

The ornamental design for a suspended stage chair, as shown and described.

WALTER B. BARROWS.
